STREET SWEEPER DIRT BOX ASSEMBLY

Robert F. Schmidt, Elgin, Henry A. Leidecker, Wheaton, and Donald G. Kirk, Elgin, Ill., assignors to Elgin Sweeper Company, Elgin, Ill., a corporation of Delaware

Filed Apr. 14, 1964, Ser. No. 359,699
20 Claims. (Cl. 15—83)

The present invention relates generally to a new and improved street sweeper. More particularly, this invention relates to a street sweeper having new and improved mechanisms for dumping a dirt hopper at a street level position or at an elevated position to permit sweepings to be loaded into a truck standing by or to be stacked in large rather than small piles. Still another important object of this invention is to provide a street sweeper which can also be operated as a front end loader for loading the sweepings directly into a truck.

A very important object of this invention is to provide a street sweeper having a front end unloader which has excellent stability during the dumping cycle without requiring any counterbalancing of the load in the dirt hopper.

A still further object of this invention is to provide a street sweeper with a front end unloader whereby the dirt hopper can be raised to an elevated position and then moved through an arc away from the sweeper so that the sweepings can be dumped as the gravity actuated door is swung open.

An important advantage of the present sweeper over prior art sweepers is that the maximum load in the dirt hopper is at no time located at the maximum extended position of the hopper during the dumping cycle, for when the dirt hopper is moved through the arc in the dumping position the dump door is simultaneously opening and the sweepings are being unloaded.

An important object of this invention is to provide a new and improved dirt hopper handling mechanism which is of compact construction so as to occupy the smallest possible area in order that a larger sized dirt hopper can be used.

Another important object of this invention is to provide a new and improved dirt hopper handling mechanism which will not interfere with the operator's view and which can be operated to unload a dirt hopper from an elevated position or at ground level. By providing a sweeper that can be unloaded from an elevated position, the sweepings can be unloaded directly into a truck or any other suitable vehicle standing by to minimize the handling of the swept material.

Yet another important object of this invention is to provide a new and improved street sweeper which is of such construction so as to permit the operator to elevate the dirt hopper from the operator's seat so that the operator can then visually determine whether the dirt hopper is fully loaded. In the past, where the operator wishes to determine whether the dirt hopper is fully loaded, it has been necessary for him to step down off the sweeper and open a side door in the dirt box in order to inspect the contents of the hopper.

In the past, especially in large city areas, the effectiveness of street sweepers has been reduced, for a great amount of time has been and still is being consumed by the sweepers in transporting loaded dirt hoppers to remote or rural dump areas. By using the sweeper for long daily periods as a truck rather than as a sweeper, the effectiveness of each sweeper is reduced. According to another important object of this invention, our sweeper is provided with a dirt hopper which can be used as a front end loader by operation of a new and improved dirt hopper handling mechanism. It is now possible with our

new sweeper to unload a filled dirt hopper into a truck or on the street in the area being swept so that the sweeper can be continuously used as a sweeper for longer periods. If a truck or other suitable hauling means is unavailable when the dirt hopper becomes fully loaded, the dirt can be dumped until a truck becomes available at which time the dirt hopper can be utilized as a front end loader to pick up and load the previously dumped sweepings into the truck.

According to important features of this invention, the dirt hopper handling mechanism includes a pair of dirt hopper carrying beams on opposite sides of the dirt box and means for elevating the dirt hopper carrying beams and means carried by the beams for rotating the dirt hopper to unload the same.

According to more specific features of this invention, the means for elevating the dirt hopper carrying beam and the means carried by the beam for rotating the dirt hopper are all disposed in a common vertical plane so as to occupy the least possible amount of space in order that the capacity of the dirt hopper may be maintained as large as possible.

According to other important features of this invention, the dirt hopper is provided with a sweepings inlet that is partially defined by a scoop so that when the dirt hopper is rotated, the dirt hopper can be used as a front end loader.

Other objects and features of this invention will more fully become apparent in view of the following detailed description taken in conjunction with the accompanying drawings illustrating therein a single embodiment and in which:

On the drawings:

FIGURE 1 is a side elevation of a street sweeper;
FIGURE 2 is an enlarged fragmentary perspective view of the street sweeper shown in FIGURE 1 with parts broken away to illustrate a dirt hopper handling mechanism embodying important features of this invention;

FIGURE 3 is an enlarged fragmentary view similar to FIGURE 2 only illustrating the manner in which the dirt hopper can be rotated or moved through an arc to unload sweepings;

FIGURE 4 is an enlarged fragmentary view similar to FIGURES 2 and 3 only illustrating the manner in which the dirt hopper handling mechanism may be operated to elevate and then rotate the dirt hopper to unload the sweepings into larger sized piles;

FIGURE 5 is an enlarged fragmentary side elevation of the street sweeper shown in FIGURE 1 illustrating in full and dotted lines the manner in which the dirt hopper handling mechanism can be operated to unload the dirt hopper;

FIGURE 6 is an enlarged fragmentary side elevation illustrating in full and dotted lines the manner in which the dirt hopper handling mechanism can be operated to place the dirt hopper in a position so that it can be used as a front end loader; and

FIGURE 7 is a top plan view of the street sweeper shown in FIGURE 1.

As shown on the drawings:

A street sweeper 10 is illustrated as having a sweeper body 11 supported on front and rear wheels 12 and 13. One or more side brooms 14 and a main broom 15 are provided for depositing sweepings onto a conveyor 16 (FIGURE 5) so that the sweepings may be deposited into a dirt hopper 17. The controls for operating the sweeper 10, the brooms 14 and 15, the conveyor 16 and the dirt box 17 are operable from an operator's seat 18 (FIGURE 7).

The dirt hopper 17 has a bottom 19, an upwardly inclined forward wall 20 and an upwardly and rearwardly inclined wall 21 with a hopper door 22 pivotally joined

at its upper end by means of hinges 23. A hopper scoop 24 lies in the plane of the upwardly and rearwardly inclined wall 21. The scoop 24 further defines a sweepings inlet 25 (FIGURE 6). The dirt hopper 17 further includes a rear wall 26 and side walls 27. When the dirt hopper is in sweeping position, the scoop snugly cooperates with upper sweeper body wall 28 to prevent dust from escaping the dirt hopper 17 as it is being loaded by the conveyor 16.

The sweeper body 11 additionally includes side body portions 30 and 31 which are joined with the upper sweeper body wall 28 and extend forwardly thereof to define a dirt hopper housing 32 (FIGURE 4). In order to mount the dirt hopper 17 on the machine, we have developed a new and improved dirt hopper handling mechanism or apparatus embodying important features of this invention. This apparatus or mechanism includes the following described components. A pair of dirt hopper carrying hollow side beams or arms 33 and 34 are pivotally joined to the side body portions 30 and 31 at pivots 35 and 36. The beams 33 and 34 are joined at opposite ends with the side walls 27 of the dirt hopper 17 at pivots 37 and 38.

A pair of fluid cylinders 39 and 40 having rams 41 and 42 are provided for raising and lowering the beams 33 and 34 and the dirt hopper 17 carried thereon. The cylinders 39 and 40 are each pivotally supported on pivots 43 at one end on the sweeper body 11 and the rams 41 and 42 each project into a hollow area 45 of the associated beam. The rams 41 and 42 are joined with the beams 33 and 34 at pivots 44. Each of the rams and its associated beam are disposed in a common vertical plane so that the elevating mechanisms may be as compact as possible. By providing compact elevating mechanisms, the largest possible dirt hopper 17 may be used on the sweeper machine 10.

Linkage and means are also provided to roll over or for rotating the dirt hopper 17 on the beams 33 and 34 to dump the contents of the hopper past the swinging door 22 through the dirt box outlet. This linkage and dirt hopper rotating means at each side of the dirt hopper are also disposed in vertical planes common with the vertical planes of the beams 33 and 34 for compactness as previously described. To this end, identical linkages 50 and 51 are provided on opposite sides of the dirt hopper 17. Since the linkages 50 and 51 are identical a description of one will suffice for both.

The linkage 51 includes a pair of first spaced parallel links 53 (FIGURE 5) which are joined at one end at pivots 54 to opposite sides of the associated beam 34. A second link 55 is joined at one end at pivot 56 between and with opposite ends of the spaced links 53 and at an opposite end at pivot 57 with the side wall 27 of the dirt hopper 17.

Mounted on the beams 33 and 34 and cooperable with the linkages 50 and 51 are a pair of fluid cylinders 60 and 61 (FIGURE 7) for rotating the dirt hopper 17. The cylinders 60 and 61 are pivotally joined with the beams 33 and 34 at pivots 64 and 65 and the rams 62 and 63 are pivotally joined with the linkages 50 and 51 at pivots 66 and 67 and more particularly with the links 53.

The scoop 24 also serves another important function in that it provides a body housing closure to prevent dust from escaping from the sweeper as the machine 10 is being used to sweep the streets. It will be appreciated that the scoop 24 may be eliminated, if desired, as the scoop is an optional feature.

Some of the advantages of our new sweeper are evident from the drawings wherein the different uses of the machine are illustrated. FIGURE 5 illustrates the manner in which the dirt hopper 17 can be elevated and dumped so that sweepings may be dumped directly into a truck, or railroad car or other type vehicle so that a savings may be effected in the handling of the sweepings. Where a truck is unavailable the sweepings can be dumped into

large piles rather than in many small piles. Either type of operation is particularly useful in city areas where dump areas are scarce and expensive. By providing a sweeping machine that can dump in such a way that large piles can be produced, the dump areas can be more efficiently utilized. When the dirt hopper 17 is turned upside down, the door 22 flops open and the contents of the hopper are emptied.

FIGURES 2 and 3 illustrate the manner in which the dirt hopper 17 can be emptied where it is not desired to unload the dirt hopper 17 from an elevated position, such as on a windy day.

Our sweeper machine 10 can also be effectively used as a front end loader for dozing or pickup operations if desired, as illustrated in FIGURE 6. Where the machine is to be used in this manner, the hopper door should be latched in position by latch bolts 70 as shown in FIGURE 7. The bolts pass through latch plates 71 and 72 secured with the door 22 and the hopper 17, respectively. As the dirt hopper 17 is moved in a pickup operation, rocks, sweepings and other materials are caused to flow through the dirt box opening normally employed as an inlet for sweepings when the machine 10 is being operated as a street sweeper.

By providing a front end loader on the sweeper, the sweeper can be used for longer daily periods as a street sweeper since the travel time of a loaded sweeper from the sweeping area to a dump area can be greatly reduced. The loaded sweeper can dump directly into a truck or dump locally in the streets until trucks arrive to carry off the accumulated sweepings. When hauling vehicles become available the front end loader on the sweeper can be used to pick up the piles of sweepings and load them thereon. In the past, especially around large cities, it has been necessary for the sweeper operators to drive long distances to dump loaded dirt hoppers, thus reducing the amount of time per day that the sweeper could be used in sweeping the streets.

When the hopper has a maximum load and it is elevated the center of gravity of the load is maintained in close proximity to the sweeper so that the load will be stabilized at all times and so that it is not necessary to provide accessory counterbalancing means on the opposite end of the sweeper. When the hopper is unloaded and rotated away from the sweeper the balance of the sweeper is not upset as the hopper is unloaded while the hopper is being rotated.

Although minor modifications might be suggested by those versed in the art, it should be understood that we wish to embody within the scope of the patent warranted hereon, all such modifications as reasonably and properly come within the scope of our contribution to the art.

We claim as our invention:

1. In combination in a street sweeping machine, a body having a pair of spaced side body portions disposed at a forward end of the sweeper defining an upwardly and forwardly opening dirt hopper housing, means for sweeping a surface over which the machine is directed and delivering the sweepings to said dirt hopper housing, a dirt hopper disposed in said housing and having a swingably mounted hopper door extended along an upper surface of the dirt hopper and having a sweepings inlet positioned rearwardly of the swingable door for receiving sweepings from said means, means comprising a pair of hollow side arms for suspending the dirt hopper from the machine with said arms being mounted on arm pivots at rearward ends on said side body portions and pivotally attached at opposite ends with opposite sides of said dirt hopper, means for pivoting said arms on said arm pivots for raising and lowering said dirt hopper comprising a first pair of fluid cylinders each attached to said body and having a ram extended into a hollow area in an associated one of said hollow side arms and

joined in coplanar relation therewith for compactness, and

means coplanar with said arms for rotating said dirt hopper on its pivots where joined with said hollow side arms comprising linkage on opposite sides of said dirt hopper joining said arms with said hopper and a second pair of fluid cylinders including a second pair of rams with said second pair of fluid cylinders joined at ends with said arms and with said second pair of rams joined at opposite ends with said linkages 5

whereby the dirt hopper may be elevated and moved through an arc to turn the dirt hopper upside down to allow the hopper door to swing open for the sweepings to fall through a discharge outlet. 15

2. In combination in a street sweeping machine, a body provided with an upwardly and forwardly opening dirt hopper housing, a dirt hopper disposed in said housing and having a swingably mounted hopper door extended along an upper surface of the dirt hopper and having a sweepings inlet positioned rearwardly of the swingable door for receiving sweepings, 20

a scoop mounted over said inlet to permit the dirt hopper to be used as a front end loader, 25

means comprising a pair of side arms for suspending the dirt hopper from the machine with said arms being mounted on arm pivots at rearward ends on said body portions and pivotally attached at opposite ends with opposite sides of said dirt hopper, 30

means for pivoting said arms on said arm pivots for raising and lowering said dirt hopper comprising a first pair of fluid cylinders attached to said body and having rams attached to said side arms on opposite sides of said hopper and disposed in coplanar relation with said arms therewith for compactness, and 35

means coplanar with said arms for rotating said dirt hopper on its pivots where joined with said side arms comprising linkage on opposite sides of said dirt hopper joining said arms with said hopper and a second pair of fluid cylinders including a second pair of rams with said second pair of fluid cylinders joined at ends with said arms and with said second pair of rams joined at opposite ends with said linkages 40

whereby the dirt hopper may be elevated and moved through an arc to turn the dirt hopper upside down to allow the hopper door to swing open for the sweepings to fall through a discharge outlet. 45

3. The combination of claim 2 further characterized by the body being provided with means for holding the hopper door in a closed position when the dirt hopper is to be used as a front end loader. 50

4. The combination of claim 2 further characterized by said scoop being snugly fitted with said body in overlying relation with respect to the conveyor to provide a closure for preventing dust and sweepings from escaping through the dirt hopper housing. 55

5. In a street sweeping machine, a body provided with an upwardly and forwardly opening dirt hopper housing, means for sweeping a surface over which the machine is directed and delivering the sweepings to said dirt hopper housing, 60

a dirt hopper disposed in said housing and having a swingably mounted hopper door extended along an upper surface of the dirt hopper and having a sweepings inlet positioned rearwardly of the swingable door for receiving sweepings from said means, 65

means comprising a pair of side arms for suspending the dirt hopper from the body with said arms being mounted on arm pivots at rearward ends on said body and pivotally attached at opposite ends with opposite sides of said dirt hopper, 70

means for pivoting said arms on said arm pivots for raising and lowering said dirt hopper comprising a first pair of fluid cylinders pivotally attached to said 75

body and to said side arms and joined in coplanar relation therewith for compactness, and

means coplanar with said arms for rotating said dirt hopper on its pivots where joined with said side arms comprising linkage on opposite sides of said dirt hopper joining said arms with said hopper and a second pair of fluid cylinders joined at ends with said arms and joined at opposite ends with said linkages whereby the dirt hopper may be elevated and moved through an arc to turn the dirt hopper upside down to allow the hopper door to swing open for the sweepings to fall through a discharge outlet.

6. A street sweeper comprising, a body having a body opening for a dirt hopper, a dirt hopper provided with a sweepings inlet mounted in said body opening, a scoop provided on said dirt hopper adjacent said sweepings inlet, means joining said dirt hopper with said body for elevating said dirt hopper, means for directing sweepings into said sweepings inlet, and means for moving said dirt hopper in an arc to position said scoop at ground level enabling the dirt hopper to be used as a front end loader.

7. In a street sweeping machine, a body provided with an upwardly and outwardly opening dirt hopper housing, a dirt hopper disposed in said housing and having a swingably mounted hopper door extended along an upper surface of the dirt hopper with the door mounted over a discharge outlet, the hopper having a sweepings inlet positioned rearwardly of the swingable door for receiving sweepings, means comprising a pair of side arms for suspending the dirt hopper from the machine with said arms being mounted on arm pivots at rearward ends on said body and pivotally attached at opposite ends with opposite sides of said dirt hopper, means for pivoting said arms on said arm pivots for raising and lowering said dirt hopper and disposed in coplanar relation with said arms for compactness, and means coplanar with said arms for compactness for rotating said dirt hopper on its pivots where joined with said side arms causing the dirt hopper to be moved through an arc to turn the dirt hopper to allow the sweepings to fall through said discharge outlet.

8. In a street sweeping machine, a body provided with an upwardly and outwardly opening dirt hopper housing, a dirt hopper disposed in said housing and having a discharge outlet and a swingably mounted hopper door covering said discharge outlet and having a sweepings inlet positioned adjacent the swingable door for receiving sweepings, means for conveying sweepings through said inlet, means comprising a pair of side arms for suspending the dirt hopper from the machine with said arms being mounted on arm pivots at rearward ends on said body and pivotally attached at remote points with opposite sides of said dirt hopper, means for pivoting said arms on said arm pivots for raising and lowering said arms and said dirt hopper, and means for rotating said dirt hopper on its pivots where joined with said side arms outwardly and away from outer ends of said side arms to turn the dirt hopper to position said discharge outlet for dumping.

9. In a street sweeping machine, a body defining an upwardly and outwardly opening dirt hopper housing, a dirt hopper disposed in said housing and having a swingably mounted hopper door and a sweepings

outlet covered thereby and having a sweepings inlet positioned adjacent the swingable door, means for sweeping a surface over which the machine is directed and delivering the sweepings through said sweepings inlet, means comprising a pair of side arms pivotally joined with the body and with the dirt hopper, means for pivoting said arms for raising and lowering said dirt hopper and positioned in coplanar relation with said arms, and means coplanar with said arms for pivoting said dirt hopper outwardly away from outer ends of said side arms comprising linkage on opposite sides of said dirt hopper joining said arms with said hopper and a pair of fluid cylinders joined with said arms and with said linkages to turn the dirt hopper to position said sweepings outlet for dumping.

10. A street sweeper comprising, a body, a dirt hopper provided with a sweepings inlet and a discharge outlet adjacent thereto, means for directing sweepings into said sweepings inlet, arm means joining said dirt hopper with said body, means for elevating said dirt hopper, and means for turning said dirt hopper over and outwardly beyond said arm means to place the dirt hopper in an unloading position.

11. A street sweeper comprising, a body having a body opening for a dirt hopper, a dirt hopper provided with a sweepings inlet mounted in said body opening and a gravity operated door adjacent thereto that is normally closed, means for directing sweepings into said sweepings inlet, arm means joining said dirt hopper with said body and means for elevating said dirt hopper, and means for moving said dirt hopper in an arc in a direction away from said body causing said gravity operated door to swing open to unload the dirt hopper.

12. A street sweeper comprising, a body having a body opening for a dirt hopper, a dirt hopper provided with a sweepings inlet mounted in said body opening and a gravity operated door adjacent thereto that is normally closed, means for directing sweepings into said sweepings inlet, arm means joining said dirt hopper with said body and means for elevating said dirt hopper, and means for moving said dirt hopper relative to said arm means in an arc in a direction away from said body causing said gravity operated door to swing open to unload the dirt hopper when the dirt hopper is in an elevated position or when the dirt hopper is disposed at ground level.

13. A front end unloader comprising, a body having a body opening for a dirt hopper, a dirt hopper provided with a sweepings inlet mounted in said body opening, means for directing sweepings into said sweepings inlet, means including arm means joining said dirt hopper with said body for elevating said dirt hopper, and means for rolling over said dirt hopper relative to said arm means in a direction away from the body and for positioning the dirt hopper outwardly of said arm means in an unloading position so that sweepings can be unloaded free of the body.

14. In a street sweeper comprising, a body having a body opening for a dirt hopper, a dirt hopper provided with a sweepings inlet mounted in said body opening along a rear edge of the hopper, means for directing sweepings into said sweepings inlet, a hopper door pivotally mounted generally on a top side of said dirt hopper, means joining said dirt hopper with said body for elevating said dirt hopper, and means for rotating said dirt hopper through an arc in a direction outwardly and away from the body

causing the hopper door to be moved from a top side position to a gravity unloading position whereby the contents of the hopper can fall free of the hopper upon pivoting of the hopper door.

15. In a street sweeper comprising, a body having a body opening for a dirt hopper, a dirt hopper provided with a sweepings inlet mounted in said body opening along a rear edge of the hopper, means for directing sweepings into said sweepings inlet, a hopper door pivotally mounted generally on a top side of said dirt hopper, means joining said dirt hopper with said body for elevating said dirt hopper and with said dirt hopper having pivots on opposite sides disposed generally beneath the hopper door, and means for rotating said dirt hopper on its pivots through an arc in a direction outwardly and away from the body causing the hopper door to be moved in an arc from a closed top side position to a gravity unloading position whereby the contents of the hopper can fall free of the hopper upon pivoting of the hopper door.

16. A street sweeper comprising, a body, a dirt hopper provided with a sweepings inlet for attachment to said body, a scoop provided on said dirt hopper positioned to allow said scoop to load said hopper, means for directing sweepings into said sweepings inlet, means joining said dirt hopper with said body, means for elevating said dirt hopper when unloading said hopper, and means for moving said dirt hopper to position said scoop at ground level enabling the dirt hopper to be used as a front end loader.

17. A street sweeper comprising, a body, a dirt hopper provided with a sweepings inlet, means for directing sweepings into said sweepings inlet, a gravity operated door on an upper end of said dirt hopper disposed in a closed position while loading said hopper with sweepings, arm means joining said dirt hopper with said body, means for elevating said dirt hopper, and means for rolling over said dirt hopper and said gravity operated door relative to said arm means in an arc in a direction away from said body for unloading the dirt hopper as the door is moved from a closed position to an open position.

18. A street sweeper comprising, a body, a dirt hopper provided with a sweepings inlet, support means joining said dirt hopper with said body, means for directing sweepings into said sweepings inlet, a dump door positioned generally top side of the dirt hopper, means for elevating said dirt hopper, and means for rolling over said dirt hopper relative to said support means in a direction away from said body placing the dirt hopper and its door in a position for dumping.

19. A front end unloader comprising, a body, a dirt hopper provided with a sweepings inlet, arm means joining said dirt hopper with said body, means for directing sweepings into said sweepings inlet, means cooperable with said arm means for elevating said dirt hopper, and means for rolling over and outwardly said dirt hopper relative to said arm means to position the dirt hopper in an unloading position.

20. In a street sweeping machine, a body defining an upwardly and outwardly opening dirt hopper housing, a dirt hopper disposed in said housing and having a

swingable discharge door and a sweepings inlet positioned adjacent the swingable door, means for sweeping a surface over which the machine is directed and delivering the sweepings through said sweepings inlet, means comprising a pair of side arms pivotally joined with the body and with the dirt hopper, means for pivoting said arms for raising and lowering said dirt hopper and positioned in coplanar relation with said arms, and means coplanar with said arms for rolling over said dirt hopper outwardly away from outer ends of said side arms for moving said hopper into an unloading

5

10

position comprising linkage on opposite sides of said dirt hopper joining said arms with said hopper.
